UNITED STATES PATENT OFFICE.

WILLIAM C. WHITCOMB, OF CHICAGO, ILLINOIS, ASSIGNOR TO GEO. D. WHITCOMB COMPANY,
OF ROCHELLE, ILLINOIS, A CORPORATION OF ILLINOIS.

MOTOR-ACTUATED HAND-TOOL.

No. 908,921.

Specification of Letters Patent.

Patented Jan. 5, 1909.

Application filed November 13, 1906. Serial No. 343,246.

To all whom it may concern:

Be it known that I, WILLIAM C. WHITCOMB, a citizen of the United States, and resident of Chicago, county of Cook, and 5 State of Illinois, have invented certain new and useful Improvements in Motor-Actuated Hand-Tools, of which the following is a specification, and which are illustrated in the accompanying drawings, forming a part thereof.

10 The invention relates to hand tools of that type in which there is incorporated with the tool an actuating motor, and, more especially, to tools of that class having an oscillatable grip and means operated by the movement 15 of the grip for controlling the supply of power fluid delivered to the motor of the tool.

The object of the invention is to improve and simplify the construction of tools of this kind, and the invention consists in a structure which is exemplified by the devices to be hereinafter described and illustrated in the accompanying drawings, in which—

Figure 1 is a central longitudinal section of a hand tool constructed according to the 25 invention; Figs. 2 and 3 are sectional views taken on the lines 2—2 and 3—3, respectively, of Fig. 1; Fig. 4 is a detail side elevation of a tool illustrating a modified form of the invention; Fig. 5 is a sectional view of the 30 same, the plane of the section being indicated by the line 5—5 of Fig. 4; and Figs. 6 and 7 are detail sectional views taken on the lines 6—6 and 7—7, respectively, of Fig. 5.

The tools illustrated in the drawings are 35 of that form employed in mining operations for drilling and cutting rock or other hard material. Each comprises a cylindrical body 10, which forms the shell of a motor having a reciprocable piston 14, and has at its forward 40 end a socket 11 for receiving the head 12 of a drilling cutter 13. The piston 14 ordinarily takes the form of a plunger for striking the head of the cutter, and is reciprocated within the chamber of the motor by a power fluid 45 in the manner well known in devices of this kind.

In order that the tool may be firmly grasped by the hand of the user, it is preferably provided with a grip stock. That of the 50 tool illustrated in Figs. 1 to 3 inclusive of the drawings is of yoke form and comprises two arms 15, 16, which spring from the wall of the cylindrical body 10 adjacent its upper end, and a cross-member or spindle 17 which

is rotatably mounted in the arms 15, 16, of 55 the yoke and carries a grip piece 18.

A duct 19 for a power fluid leads from a nipple 20, provided for attachment to the source of power supply and preferably formed on the body of the tool at the base of 60 one of the arms, as 15, of the grip stock, through the wall of the tool to the chamber of the motor. As shown this duct is provided with a forwardly-directed valve seat 21, and coöperating with this seat to control 65 the duct is a valve 22, normally closed by a spring 23. A valve-stem 24 extends upwardly from the face of the valve 22, across the duct 19 and through the arm 15 of the handle of the tool into operative engagement 70 with the spindle 17 to open the valve.

Preferably a cam 25 is formed on one end of the spindle 17 to engage the valve stem. As is most clearly shown in Fig. 2 of the drawings, this cam is housed within the outer 75 end of the arm 15 and is provided with a recess 26 for receiving the end of the valve stem and thereby forming a catch for maintaining the valve in the open position.

As shown, the valve 22 is faced with a 80 quantity of yielding material 27 and the valve is rendered adjustable on the valve stem by means of a follower 28, which has a threaded engagement with the stem behind the valve. Leakage from the duct 19 through 85 the arm 15 of the handle of the tool is prevented by means of a shoulder 29 formed on the valve stem 24. This shoulder is faced with a quantity of packing material 30, and this packing is held to its seat against the face 90 of the shoulder 29 by a sleeve 31 inclosing the valve stem and reacting against the face of the valve 22.

If desired a gear connection between the 95 stem of the motor valve and the grip member of the handle of the tool may be provided, as is illustrated in Figs. 4 to 7 inclusive of the drawings. In this form of construction the cylindrical body 10 of the tool is preferably provided with a handle or grip-stock in yoke 100 form and comprising arms 32, 33, which spring from the wall of the body adjacent its upper end.

A duct 34 for a power fluid leads from a nipple 35 formed on the wall of the body of 105 the tool, preferably adjacent the base of the arm 32 of the handle, to the chamber of the motor. As shown, this duct is controlled by

a valve which takes the form of a plunger 36 movable across the duct, and has a stem 37 which extends upwardly through the arm 32 of the handle of the tool. An oscillatable 5 grip piece 38 is provided for grasping the tool and, as in the form of construction previously described, this is preferably carried by a spindle 39 rotatably mounted in the arms 32, 33, of the stock. In this instance operative 10 connection between the grip piece 38 and the valve stem 37 is established by means of a gear 40 formed on one end of the spindle 39 and housed within the outer end of the arm 32 of the stock, and a gear rack 41 formed on 15 the valve stem.

As is most clearly shown in Fig. 4 of the drawings, the arm 32 of the handle is inclined to the axis of the tool in order that the gear rack 41 may be sufficiently removed from the 20 center line of the grip 38 to engage the periphery of the gear 40. For convenience in the manufacture and assembling of the parts, the gear rack 41 takes the form of a screw-thread turned on the valve stem for a portion 25 of its length.

In use the tool will be held in the hands of an attendant who will grasp the wall of the body 10 with one hand and the grip-piece 18 or 38 with the other, and will apply pressure 30 to the tool to hold the cutter 13 to its work. By a slight rotation of the grip piece 18 or 38 he may easily control the delivery of power fluid to the motor of the tool without releasing or impairing his hold.

35 I claim as my invention—

1. In a fluid-actuated hand tool, in combination, a power cylinder having a stock in yoke form, an attaching nipple formed on the wall of the cylinder at the base of one branch 40 of the yoke and a fluid duct leading from the attaching nipple to the chamber of the cylinder, a valve for controlling the duct having a stem housed within the same branch of the yoke, and a hand grip journaled in the two 45 arms of the yoke and operatively engaging the valve stem.

2. In a fluid-actuated hand tool, in combination, a power cylinder having a stock, an attaching nipple formed on the wall of the 50 cylinder at the base of the stock and a fluid duct leading from the attaching nipple to the chamber of the cylinder, a spring-closed

valve for controlling the duct and having a stem housed within the stock, and a handle for the tool oscillatably mounted in the 55 stock and operatively engaging the valve stem to open the valve.

3. In a fluid-actuated hand tool, in combination, a power cylinder having a stock, an attaching nipple formed on the wall of the 60 cylinder at the base of the stock and a fluid duct leading from the attaching nipple to the chamber of the cylinder, a spring-closed valve for controlling the duct and having a stem housed within the stock, and a handle 65 for the tool rotatably mounted in the stock and having a cam for engaging the valve stem to open the valve.

4. In a fluid-actuated hand tool, in combination, a power cylinder having a stock and 70 a fluid duct entering through the wall of the cylinder at the base of the stock, a spring-closed valve for controlling the duct and having a stem housed within the stock, a handle for the tool rotatably mounted in the 75 stock, and a cam carried by the handle for engaging the end of the valve stem to open the valve and having a recess for receiving the end of the valve stem when the valve is in 80 the open position.

5. In combination, a fluid duct having a valve seat and an aperture in its wall in front of the seat, a valve stem extending through the aperture, a packing shoulder and a valve mounted on the stem for relative adjustment, 85 a packing carried by the stem and co-operating with the shoulder to close the aperture in the wall of the duct, and a sleeve inclosing the valve stem and reacting between the valve and the stem.

6. In combination, a fluid duct having a valve seat and an aperture in its wall in front of the seat, a valve stem extending through the aperture and having a packing shoulder, a valve adjustably mounted on the stem, a 95 packing carried by the stem and co-operating with the shoulder to close the aperture in the wall of the duct, and a sleeve inclosing the valve stem and reacting between the valve and the packing.

WILLIAM C. WHITCOMB.
